UNITED STATES PATENT OFFICE.

GEORGE H. HYDE, OF WATERTOWN, NEW YORK, ASSIGNOR TO THE HYDE METAL BOAT COMPANY, OF WATERTOWN, NEW YORK, A CORPORATION OF NEW YORK.

APPARATUS FOR DEFORMING SHEET-METAL PLATES.

Specification of Letters Patent. Patented July 16, 1912.

1,032,907.

Application filed December 8, 1910. Serial No. 596,332.

To all whom it may concern:

Be it known that I, GEORGE H. HYDE, of Watertown, in the county of Jefferson, in the State of New York, have invented new and useful Improvements in Apparatus for Deforming Sheet-Metal Plates, of which the following, taken in connection with the accompanying drawings, is a full, clear, and exact description.

10 This invention relates to certain improvements in apparatus for deforming sheet metal plates of the class set forth in my Patent #926,253 June 29, 1909 and is particularly useful in deforming the sections or 15 plates of sheet metal boats to substantially the same contour which they would assume when assembled, thereby permitting the sections of the boat to be stored or shipped in compact space and easily and quickly assembled when desired.

In my Patent #926,253 referred to, the sheet metal was deformed by pressure between a flat elastic bed plate and a suitable presser roll, thereby producing a uniform 25 pressure and consequent uniform curvature or deformation of the sheet metal as the carriage is moved back and forth, any variation from such pressure or contour being effected by vertical adjustment of the roller. I have 30 discovered, however, that by the use of a convex (either spherical or cylindrical) supporting bed for the plate and simply shifting such bed or roller laterally, I am enabled 35 to obtain a wider range or variation in the contour of the sheet metal plates without vertical adjustment of either the roller or bed, thereby producing the desired deformation more expeditiously than with a flat bed piece.

40 The main object, therefore, of my present invention is to enable the operator to subject different portions of a sheet metal plate to different pressures during the same or repetitions of the same operation of the pressing elements and to thereby materially increase 45 the output of the machine for a given period of time.

A further object is to enable the pressure 50 upon the plate to be gradually increased from one side toward a given point and then gradually reduced from such point toward another side of the plate in a single operation, thereby producing a maximum curvature or deformation of the plate at the point 55 of greatest pressure.

Another object in the use of convex pressing elements is to enable the sheet to be more easily manipulated at the end of each pressing operation in order to bring the portion thereof which requires the greatest amount 60 of deformation at the highest point of the supporting bed.

A still further object is to enable the pressure and consequent degree of deformation to be varied at will by simply shifting one 65 or the other of the pressing elements laterally, thereby varying the relative positions of their high points and angle of contact of the pressing elements.

Other objects and uses will be brought 70 out in the following description.

In the drawings—Figure 1 is a side elevation of a deforming machine embodying the various features of my invention. Fig. 2 is an enlarged sectional view of the plate supporting bed having a cylindrical convex surface, the presser roll being shown in elevation. Fig. 3 is an end elevation of a portion of the same bed showing the presser roll in section. Figs. 4 and 5 are views similar to 75 Figs. 2 and 3 except that the bed is provided with a spherical convex surface and is shown in section in Fig. 5. Fig. 6 is a sectional view of a modified form of bed having its surface curved transversely of the 80 roller or to its direction of movement, the roller being shown in section. Fig. 7 is a sectional view of a still further modified 85 form of bed showing the roller in elevation, the convex surface of the bed being more or 90 less irregular.

In Fig. 1 I have shown a main supporting frame —1— upon which is mounted a horizontally movable carriage —2— for receiving and supporting an elastic bed —3— having 95 a convex upper surface. Secured to the main frame —1— is an upright bracket —4— having a forwardly projecting extension or arm —5— upon which is mounted a transversely movable cross head —6—. Upon this cross head is mounted a vertically adjustable roller support —7— carrying a 100 presser roll —8—, the latter having a transversely convexed presser face for coaction with the convex bed —3— in deforming a 105 sheet metal plate as —a—.

The cross head —6— may be adjusted transversely of the carriage —2— to correspondingly change the position of the roller —8— relatively to the bed —3—, or the bed 110

- may be adjusted transversely or longitudinally of the carriage, the object of such adjustment being to change the relative positions or angles of the coacting presser faces and to thereby vary the pressure upon the plate without necessitating the vertical adjustment of the roller. This roller is normally positioned so that its lower contact face is in a plane below that of the high point of the supporting bed for the sheet metal so that when the bed is moved back and forth, the plate will be subjected to gradually increasing pressure toward the high point and to gradually decreasing pressure from the high point of the bed, the maximum pressure and consequently the greatest degree of curvature being at the high point.
- The bed —3— preferably consists of a plano-convex backing —9— of wood or equivalent fibrous material which is somewhat yielding but is preferably provided with a concavo-convex surface covering —10— of elastic material such as soft rubber, rubber canvas or equivalent material capable of yielding under pressure and at the same time reacting on all sides of the point of greatest pressure to give the plate under pressure the desired curvature or contour.
- 30 As shown in Figs. 2 and 3, the upper surface of the supporting bed —3— or elastic covering —10— is convexed in the direction of movement of the carriage —2— and adjacent face of the roller —8— so as to afford the gradually increasing pressure toward and gradually reduced pressure from the high point as the carriage is moved back and forth but it is evident that the convexity may be transversely of the direction of movement of the carriage.
- In Figs. 4 and 5 I have shown a backing —9— of wood or similar somewhat yielding fibrous material provided with a spherically convexed upper face upon which is mounted a similarly shaped concavo-convex covering —10— of soft rubber, rubber canvas or similar elastic material capable of yielding easily under pressure. It therefore follows that the upper surface of the sheet metal supporting bed —10— is convexed in all directions both transversely and longitudinally so that by shifting one of the pressing elements laterally, the degree of pressure and angle of contact may be varied at will according to the deformation which may be required. For example, assuming that the lower face of the roller is disposed in a plane below that of the high point of the elastic plate support, then it is clearly evident that a maximum degree of pressure would be produced at such high point but by shifting the bed or roller laterally so as to bring the point of contact outside of the high point of the bed it is evident that the pressure upon a corresponding curvature of the plate would be reduced and owing to the fact that the surface of the roll is convexed transversely the angle of contact between the roller and bed plate will also be changed, thereby affording a wider range of deformation than would be possible between the same roller and a coacting flat supporting bed.
- In Figs. 6 and 7 I have shown bed pieces —20— and —21— of wood or similar fibrous material having convex upper surfaces coacting with suitable rollers —8— and —22— but in both of these modifications, the elastic rubber coverings shown in Figs. —1— to —5— inclusive may be omitted and the sheet metal plates supported directly upon the convex upper faces of the wood. Otherwise the construction shown in Fig. —6— is substantially the same as that shown in Figs. 1, 2 and 3 except that the upper face of the bed piece —20— is convexed transversely of the direction of movement of the bed.
- The roller —22— shown in Fig. —7— is somewhat conical or concaved to conform approximately to the convex face of the bed piece —21—. The object, however, is to produce a maximum pressure on the plate at the high point of the bed piece and to enable this pressure to be varied by lateral shifting of the roller or bed piece. In this latter modification different portions of the curved faces of the bed piece and roller are of different radii to allow a wider range of deformation of the plates by simply shifting the bed piece or roller laterally, that is, by the use of a bed piece having a convex surface curved on different radii, I am enabled to deform the plates under widely varying degrees of curvature but in all of the modifications, the plate will be curved or deformed both longitudinally and transversely or parallel with and transversely of the axis of the roller or direction of movement of the carriage.
- When it is desired to expand or stretch one or more edges of a sheet metal plate, as, for instance, in conforming such plate to the bow of a boat, the edge to be stretched or expanded may be placed upon the cylindrical bed —10—, Figs. 2 and 3 and subjected to repeated pressing operations of the roller —8— at different points and at substantially right angles to the edge to be stretched until the desired length is produced, whereupon such edge may be again subjected to pressure between the bed —21— and roller —22—, shown in Fig. —7— for additionally stretching and at the same time smoothing the same to the desired contour or flare, while in practically all other operations, the sheets are given a concavo-convex form of greater or less curvature in different directions according to the deformation required.
- By using the structure shown in Fig. 6, I am enabled to produce a sharper curve be-

cause the pressure decreases much more rapidly out from the point of greatest pressure. It is to be understood, however, that the present invention lies broadly in the use of a supporting bed having a convex surface of regular or irregular curvature and that while the surface of the roller is preferably convex in cross section, it may be conical as shown in Fig. 7, the object being to enable the plates to be subjected to a maximum pressure at the high point or points of the bed and to gradually reduce laterally from such high points so as to produce the desired stretching or deformation at any part of the plate, and although I have shown specific forms of beds and rollers adapted for deforming the plates of sheet metal boats, it is evident that the same apparatus may be used in the manufacture of plates for any other purpose, such, for example, as fenders and other sheet metal parts of automobiles and therefore I do not limit myself to the exact construction and arrangement of the parts

as shown and described nor to the manufacture of the particular articles which this apparatus is capable of producing. 25

What I claim is:

An apparatus for deforming sheet metal plates comprising a non-rotatable elastic supporting bed for the plates, and a presser 30 roll coating therewith and provided with a transversely curved face, the surface of said bed being curved transversely of the axis of the roll, and means for moving one of the elements in the direction of length of the 35 surface of the bed gradually varying the degree of pressure on the plate as the points of pressure approach or recede from the high points in the curvature of the bed.

In witness whereof I have hereunto set 40 my hand on this second day of December 1910.

GEORGE H. HYDE.
